REMOVABLE DOUBLE-HUNG WINDOW SASHES

Harry W. Suleski, Milwaukee, Wis.

Application November 2, 1956, Serial No. 619,971

3 Claims. (Cl. 20—52.3)

2

Figures 5 and 6 are fragmentary perspective views of one of the sashes showing the sash mounting strip in locked and unlocked positions respectively.

Referring to the drawings in detail, designated generally at 10, 12 are upper and lower sashes of a double-hung window the frame of which has been generally designated at 14. Frame 14 includes the usual sill 16, header 18, and side jambs 20, 20.

At the outside of the window frame, a molding 22 (see

10 Figures 2 and 4) extends through the full periphery of the window frame, said molding having an inner edge portion 23 projecting inwardly of the window frame, to prevent removal of the sashes from the outside of the building structure and, further, to serve as a guide for the slidable movement of the upper sash as best shown in Figure 2. On the inner surface of the molding 22, there is formed a continuous groove 24, receiving tongues formed upon the outer edge surfaces of the side jambs and header, said tongues being designated at 25.

15 20 As shown in Figure 4, in the inner surfaces of the side jambs there are formed grooves 28, and mountable in said grooves are guide strips 30, formed of metal by extrusion or by any other suitable process, said guide strips 30 being secured in place by wood screws 32 (see Figure 4) passing 25 through the webs of the respective guide strips and engaged in the side jambs 20. At opposite sides of the webs of the strips, there are formed channels 34, so that said strips are of double-channeled construction, as will be shown to particular advantage in Figures 1 and 4.

20 30 Referring to the upper sash 10, at one side this is provided with a locking strip or plate 38 extending the full height of the upper sash. Locking strip 36, as shown in Figure 1, has an outwardly offset outer edge portion 38 projecting outwardly beyond the adjacent side edge of the 35 upper sash. The strip 36 is secured to the sash 10 by means of uniformly spaced screws 40, passing through short slots 42 that extend transversely of the strip 36. The strip 36, thus, is mounted for lateral displacement, between a locking position in which the edge portion 38 projects outwardly beyond the side of the sash in the manner shown in Figure 5, and an unlocking or retracted position in which the outer longitudinal edge of strip 36 is flush with the adjacent side edge of the sash 10.

35 40 In Figure 1, the sashes are seen from the inside of the building, and it will be noted that the combined mounting, locking and weather stripping plates are on the inner side of the upper sash and on the outer side of the lower sash. Further, the upper sash has a movable plate along its right hand side rail while the lower sash has an identically but oppositely formed movable plate along its left hand side edge. The upper sash 10 has a stationary plate along its left hand side edge and the lower sash 12 has a stationary plate along its right hand side edge.

45 50 55 Spaced longitudinally of the plate 36 are two short longitudinal slots 44. These provide cam slots receiving eccentric lugs 46 projecting inwardly of the building from disc-shaped heads 48 of pins 50 rotating in through openings 51 of the upper sash. The other ends of the pins are exposed to the inside of the building and are formed with kerfs for receiving a screw driver bit. Other means facilitating rotation of the pins, as for example levers or handles, could be provided on the pins.

55 60 65 The outer edge portion of plate 36 is extendable to its Figure 5 position into the outer channel 34 of guide strip 30, by rotating pins 50 in one direction, and is retractable from the channel to its Figure 6 position by rotating the pins in an opposite direction. This is effected by the motion-translating linkage constituted by the pins 50, eccentric lugs 30, and slots 44, adapted to 70 convert rotary motion of the pins into lateral sliding movement of plate 36 on screws 40 between opposite extreme positions determined by the length of slots 42.

This invention relates generally to window sash construction, and more particularly has reference to means embodied in seemingly conventional sashes of a double-hung window, adapted to permit with speed and ease the removal or insertion of the sashes, weatherstrip the sashes, and facilitate conversion of conventional sashes.

The ordinary double-hung window has sashes that are more or less permanently mounted, and as a result, not only is the installation or disassembly of the window rendered a rather laborious and expensive procedure requiring considerable skill on the part of the worker, but also, the washing of the windows is complicated due to the difficulties of having access to the outer surfaces of the sashes.

The main object of the present invention is to provide a novel sash construction for double-hung windows, so designed that the sashes can be swiftly removed bodily from their associated frame, and as swiftly remounted within the frame. In this way, repairs or maintenance can be effected with ease, as for example the sashes can be painted or the panes thereof replaced if broken. Additionally, the washing of the windows is rendered substantially easier while promoting, at the same time, better and more complete cleaning of the sashes.

Another object is to provide sashes that will have the decided advantages noted above, while at the same time being capable of manufacture at a cost little or no greater than that required for sashes not having the mentioned features.

Another object is to provide a sash construction as stated wherein the means for permitting the removal and remounting of the sashes will be used in association with preformed, double-channel strips serving the functions of the usual parting means or strips provided in conventional double-hung window construction.

Another object is to provide means of the character stated that will be formed almost entirely from inexpensive components, particularly adapted for manufacture by mass production methods.

Still another object of importance is to provide means facilitating the removal of the sashes from a window frame which will, at the same time, constitute means for supporting the sashes within the frames and for guiding the sashes during their movement between open and closed positions.

Other objects will appear from the following description, the claims appended thereto, and from the annexed drawing, in which like reference characters designate like parts throughout the several views, and wherein:

Figure 1 is a partially exploded perspective view of a double-hung window construction according to the present invention;

Figure 2 is an enlarged vertical sectional view transversely through the window, portions being broken away;

Figure 3 is a vertical section on the same scale as Figure 2, taken substantially on line 3—3 of Figure 2;

Figure 4 is a sectional view substantially on line 4—4 of Figure 3; and

On the opposite side edge of the sash 10 there is fixedly mounted a plate 52 secured by screws 54 to the sash with its outer longitudinal edge portion projecting outwardly from the sash into the outer channel 34 of the other guide strip 30.

The plates 36, 52 thus mount the upper sash slidably in the guide strips 30 for movement between its closed and open positions. They further serve, in cooperation with the guide strips, in weatherstripping the window. In addition, they eliminate the need for sash cords and weights, due to the fact that with the movable plate partially retracted, the sash can be raised or lowered and then locked in the position to which it is moved, by rotation of the pins sufficiently to fully extend the movable plate 36 and frictionally bind the same in its associated channel 34.

The lower sash has a movable plate 56 identical but opposite to the plate 36 mounted, as previously noted, on the outside of the lower sash along the left hand side rail thereof, and adjustable laterally by pins 58 similar to pins 50. On the right hand side rail, the lower sash has a stationary plate 60 analogous to plate 52 of the upper sash.

The construction permits the sashes to be removed with maximum ease and speed, for cleaning, painting or any other purpose. Further, the construction allows the invention to be embodied in windows of conventional design that have already been installed. Conversion of a conventional, double-hung window to a window having removable, weather-stripped sashes is effected easily and speedily by first removing the usual parting strips of the side jambs and then mounting in the grooves 28, left by removal of the parting strips, the double-channeled guide strips 30. Then the sashes are drilled to receive the pins 50 and 58.

After the sashes have been drilled to receive the pins 50 and 58, and after said pins have been mounted in the position illustrated in the drawing, the sashes are inserted in the window frame from within the building and the locking strips are extended to engage the same in their associated channels 34, thus completing the conversion of a conventional window to the window illustrated and described herein.

As previously mentioned herein, the conversion is effected to provide sashes that are readily removable bodily from the window frames from the interior of the building for any desired purpose, are weather-stripped by engagement by the plates in narrow channels 34 in which they are snugly but slidably received, and are lockable in selected position by binding of the plates in the channel, without the necessity of sash cords or weights.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor change in construction that may be permitted within the scope of the appended claims.

What is claimed is:

1. In a double-hung window construction the combination, with a frame including side jambs having confronting grooves, of: means mounted in the grooves providing transversely spaced channels in each groove; a pair of window sashes having confronting surfaces lying substantially in planes including the respective grooves; plates mounted on said surfaces of the sashes for slidable engagement in the channels, at least one plate of each sash being mounted for adjustment in a horizontal direction toward and away from its associated channel, to permit bodily removal of the sashes from the frame; and means

on each of the sashes for adjusting said one plate in said direction, comprising pins mounted in the respective sashes to rotate about horizontal axes, said pins including eccentric lugs, said one plate of each sash having vertical cam slots receiving the lugs of the pins of the sash.

2. In a double-hung window construction the combination, with a frame including side jambs having confronting grooves, of: means mounted in the grooves providing transversely spaced channels in each groove; a pair of window sashes having confronting surfaces lying substantially in planes including the respective grooves; plates mounted on said surfaces of the sashes for slidable engagement in the channels, at least one plate of each sash being mounted for adjustment in a horizontal direction toward and away from its associated channel, to permit bodily removal of the sashes from the frame; and means on each of the sashes for adjusting said one plate in said direction, comprising pins mounted in the respective sashes to rotate about horizontal axes, said pins including eccentric lugs, said one plate of each sash having vertical cam slots receiving the lugs of the pins of the sash, said one plate of each sash having a plurality of horizontal slots and the sash supporting the same including support pins extending through the last named slots to provide the mounting of said one plate on the sash for horizontal adjustment, the last named slots engaging the support pins on adjustment of said one plate in either direction to limit said adjustment.

3. In a double-hung window construction the combination, with a frame including side jambs having confronting grooves, of: means mounted in the grooves providing transversely spaced channels in each groove; a pair of window sashes having confronting surfaces lying substantially in planes including the respective grooves; plates mounted on said surfaces of the sashes for slidable engagement in the channels, at least one plate of each sash being mounted for adjustment in a horizontal direction toward and away from its associated channel, to permit bodily removal of the sashes from the frame; and means on each of the sashes for adjusting said one plate in said direction, comprising pins mounted in the respective sashes to rotate about horizontal axes, said pins including eccentric lugs, said one plate of each sash having vertical cam slots receiving the lugs of the pins of the sash, said one plate of each sash having a plurality of horizontal slots and the sash supporting the same including support pins extending through the last named slots to provide the mounting of said one plate on the sash for horizontal adjustment, the last named slots engaging the support pins on adjustment of said one plate in either direction to limit said adjustment, said one plate of each sash being of planiform formation and when adjusted in said horizontal direction being shifted in its own plane, said pins having their axes perpendicular to the plane of said plate with the lug of each pin being spaced radially from the axis of the pin and traveling in a circular path in said plane on rotation of the pin, to exert a lateral pressure in said plane against the opposite side edges of the vertical slot through which the lug projects during adjustment of the plate toward and away from, respectively, its associated channel, said horizontal slot having their lengths extended in the direction of movement of said one plate during said adjustment of the plate, to hold the plate against up and down movement out of its path of horizontal adjustment during the biasing of the plate by the lugs engaged in the vertical slots thereof.
